UNITED STATES PATENT OFFICE.

THOMAS M. CHANCE, OF PHILADELPHIA, PENNSYLVANIA.

FLAME SAFETY AND OPEN LAMP.

1,323,618.

Specification of Letters Patent.

Patented Dec. 2, 1919.

Application filed April 26, 1917. Serial No. 164,675.

To all whom it may concern:

Be it known that I, THOMAS M. CHANCE, a citizen of the United States, residing at Philadelphia, in the county of Philadelphia and State of Pennsylvania, have invented a certain new and useful Improvement in Flame Safety and Open Lamps, of which the following is a specification.

The object of my invention is to provide 10 an improved type of flame safety lamp that will project a portion of the light emitted by the flame into the space above, and in some cases below, said lamp. A further object of my invention is to provide a means 15 for increasing the efficiency of the burner, in those types of lamps employing a reigniting type of burner in connection with a gaseous fuel. Another object of my invention is to provide an improved acetylene 20 generator whereby a safety lamp may be constructed that will eliminate the objectionable features hitherto encountered in lamps of this type.

To attain these ends I construct the lamp 25 to operate in the manner shown by the accompanying drawings, and described in detail in the following specification. It will be understood, however, that I do not limit myself to the particular constructions shown 30 herein, but that these types may be widely varied without departing from the spirit of my invention, and that the drawings shown herein are diagrammatic representations of the general association of elements necessary to the operation of my invention.

The drawing, Figure I, is a diagrammatic vertical cross-section of an acetylene safety lamp adapted to carry out my invention. Fig. II is a similar cross-section of a lamp 40 employing a different arrangement of reflectors and generator and a different type of burner. Fig. III is an enlarged vertical cross-section showing another type of reigniting burner. Fig. IV is a partial vertical 45 cross-section illustrating an improved type of combustion chamber. Like numbers in the several drawings indicate like parts.

In the drawing Fig. I, 1 indicates a water chamber provided with filling opening 2, 50 in this case fitted with a ball valve, and pressure escape pipe 3. The calcium carbide container 4 is fitted with water feed tube 5, and is provided with a water sealed cover 6, said cover 6 screwing into water chamber 1 and 55 supporting container 4 by screw thread 7.

Said water chamber 1 carries valve and water-feed valve stem 8 in a screw thread in the base of said chamber. Said stem 8 is provided with a conical valve face at its upper end, adapted to close communication between container 4 and the burner,—in this case a single jet steatite burner 9 provided with self-contained reigniting prongs 10 and shield 11,—mounted on cover 6. Said stem 8 is enlarged near the operating screw 60 thread at its lower end, said enlargement nearly filling feed tube 5 and providing a restricted water feed to the carbide contained in 4. This enlargement may be provided with a conical valve seat at its lower end to 65 prevent leakage of water past the operating screw thread on said stem when said stem is screwed to its lowermost position. The stem 8 is also provided with an operating head at its lower extremity. A filter 12 is held in 70 place in the top of cover 6 by filter support 13, said support 13 housing over a tube 14 surrounding valve stem 8. Said tube 14 slips into feed tube 5 when container 4 is 75 being filled with carbide (preventing the falling of carbide into said tube 5), but is lifted out of tube 5 by the enlargement on valve stem 8 when container 4 and cover 6 are 80 screwed into place in water chamber 1.

The combustion chamber, or lamp top, is 85 composed of bonnet 15, provided with standards 16 connecting said bonnet with screw ring 17. Said screw ring may be provided with a locking device 18, for locking said lamp top to the gas generator, the 90 locking device being in this case shown as of the lead rivet, slip ring type. Said screw ring 17 is provided with reflecting element 19, the function of which is further described in this specification. Glass-ring 20 screws 95 into screw ring 17 and supports a horizontal gauze 21 carrying outer glass 22 and glass chimney 23, which in turn support horizontal gauze 24 fitted with metal chimney 25, outer gauze 26 and inner gauze 27. The 100 admission of air for combustion is secured through slots 28 in the wall of bonnet 15 and gaskets 29 are placed between glass 22 and gauzes 21 and 24 to insure a gas-tight fit.

The operation of the apparatus illustrated 105 in Fig. I is as follows: Assuming carbide container 4 to be partly filled with a charge of calcium carbide. Container 4 is screwed into cover 6 by means of the thread 7, and cover 6 is then screwed in place in water chamber 110

1, feed tube 5 slipping down over valve stem 8 and tube 14 being raised by the enlargement on said stem. Water is now introduced through filling opening 2 and, the valve on stem 8 being open, generation of acetylene commences, the resulting gas passing through filter 12, and issuing at the orifice of burner 9. The lamp may now be lighted and the lamp top, assembled as shown in Fig. I, is 10 screwed in place on water chamber 1. A lead rivet is inserted in locking device 18 and the rivet upset, thus isolating the entire internal mechanism of the lamp from the exterior.

15 As the lamp gradually heats up the air for combustion is heated by passing downward through the annular space between the interior glass chimney 23 and exterior glass 22, both of these glasses becoming very 20 warm due to heat radiated and conducted from the flame. Shield 11 likewise becomes heated and, acting as a reflective element, prevents excessive dissipation of heat from the reigniting prongs 10 on burner 9.

25 If the lamp be now subjected to the concussion due to shot-firing or other rise in atmospheric pressure, the jet of gas issuing from the orifice of burner 9 will be temporarily arrested, but immediately said jet is 30 re-established, after the passing of the consecutive wave, the flame is also re-established by some portion of the mixture of acetylene and air reaching the reigniting prongs 10 during said re-establishment of the jet.

35 The function of the double glass type of combustion chamber is twofold. In the first place it assists materially in steadyng the lamp flame from the effect of exterior air currents, etc., tends to increase the efficiency of combustion by pre-heating the air supply and prevents the chimney effect commonly encountered with under-feed lamps, such as the Wolf lamp, when the lamp is introduced into atmospheres containing considerable percentages of firedamp or combustible gas. In the second place it greatly increases the safety of the lamp inasmuch as a lamp so constructed comprises virtually two lamps in one. That 40 is, if the exterior glass be broken, or even completely removed, the lamp flame is still isolated by horizontal gauze 21, inner chimney 23, upper horizontal gauze 24 and exterior and interior gauzes 26 and 27 respectively. Thus it will be readily seen that this type of lamp is more safe for use in locations where the outer glass may become accidentally fractured, as such fracture of the glass in the ordinary type of lamp may result in immediate passage of the flame to the exterior should the exterior atmosphere be inflammable. A further advantage of this construction is that the inner glass is virtually 45 spring-supported, horizontal gauzes 21 and

24 acting as resilient cushions, and I have found that while the outer glass may be broken when the lamp is dropped from a great height, due to the jar on the whole lamp structure, that the inner glass is practically immune from such breakage. It should be noted that the construction shown is well adapted to resist passage of the flame in inflammable atmospheres, as there are four gauzes which must be passed on the 70 inlet side of the lamp before the lamp can fire the exterior atmosphere, and in lamps fitted with a chimney, such as in lamps of the Muessler type, exterior ignitions are nearly always produced by passage of the 75 flame on the inlet side of the lamp, since the products of combustion in the chimney generally prevent ignitions down said chimney. While in the construction herein shown there are but two gauzes isolating the 80 discharge of the lamp from the exterior, it will thus be seen that the cushion of dead gases in chimney 25 will assist in preventing ignition on the discharge side. The chimney 25 also assists in the draft of the 85 lamp.

The reflecting element 19 serves to project a portion of the rays of light emitted from the flame in a roughly conical path upward, (the approximate path of one such ray being shown by the dot and dash line A—A) and thereby provides an illuminated area 90 immediately above the lamp, thus enabling the miner using the lamp to make a careful inspection of the condition of the roof or 95 other space above him. Such inspection has hitherto been practically impossible of accomplishment and it is a well known fact that in many districts more accidents have resulted from failure to properly inspect 100 the roof after safety lamps were introduced, than were formerly caused by ignitions of gas, due to the use of open lamps. The only way in which the roof can be inspected with safety lamps as at present constructed is by 105 tilting the lamp, and while such tilting could be practised to a moderate degree in lamps burning acetylene or other gas under pressure, it is fatal to the operation of the common type of oil burning safety lamps, 110 as it results in immediate smoking of the glass. It should be noted that the light projected by the reflecting element need not necessarily remove any considerable amount of light from the flux emitted by the flame 115 in a horizontal direction, for said element can readily be designed to make use of light that would largely be lost by absorption in the base of the lamp, and also because a portion of the light reflected by said element 19 is not reflected upward but is reflected into the glass, which in turn may partially reflect it back into said horizontal flux. It will of course be clear that an inverted conical reflector of the same type may 120

be used in the upper portion of said bonnet, as shown in Fig. II, should it be desired to illuminate the floor below the lamp.

The method of operation of the generator shown in Fig. I is similar to that commonly known as the contact method, that is, the water is introduced near the bottom of the carbid, the supply of water depending on the relation between the gas and water pressure; and the resultant excessive heating encountered in "drip" generators is lessened. Should the slacked carbid form a crust about the orifice of the water feed, this may be effectively broken up and normal conditions reestablished by rotating the valve stem 8 by means of the milled head on the lower end. This rotation will raise the valve stem up and down in feed tube 5 and perform the function commonly known as "raking" in the small generators now used for mine lighting. It will be noted that the valve stem has some play before encountering the conical seat in cover 6 so that a number of turns can be given in this raking process before shutting the gas supply off.

The function of water-sealed cover 6 is the same as that commonly performed by the cover of the bell-type of generator, that is, a water seal is provided to prevent the escape of gas, but with this important addition, that mechanical means are provided for preventing free flow of water between the water chamber and the interior of carbid container 4, should the generator be overturned. In the drawing Fig. I, such flow is prevented by means of screw thread 7, said screw thread, while not necessarily forming a gas-tight fit, providing a greatly restricted frictional resistance so that free escape of the gas is prevented and the flooding of the generator with water, should the lamp be turned on its side, eliminated. This trouble due to flooding of the lamp just referred to would be inherent in all types of water-sealed generator in common use and would effectually prevent the use of such generators in lamps of this kind. I have found, however, that by the addition of a mechanical resistance to the hydraulic seal, a generator is available that possesses the paramount advantage of gas-tightness—a condition that could never be absolutely insured in lamps employing a gasket alone for the sealing of the generator—coupled with absolute portability, that is, the generator can be overturned, swung from the hand or in other ways mistreated without seriously affecting its operation. It might be noted here that the impossibility of insuring gas-tightness in lamps using gaskets for the sealing of the generator, has so militated against the use of this type of lamp that the acetylene safety lamp as heretofore constructed has not been permitted in any of the principal mining districts of the world.

In the drawing Fig. II the generator is similar in construction to that shown in Fig. I, and need not be further described except to call attention to the fact that the mechanical resistance, shown in Fig. I as screw thread 7 is here shown as a gasket 7 placed between the carbid container 4 and cover 6, this gasket being placed in compression when cover 6 is screwed down on the carbid container 4, and also that movable tube 14 is replaced by a stationary perforated tube 14. It will of course be understood that this gasket could be placed at the lower portion of carbid container 4, and thus immersed in water, instead of in the position shown.

The burner 9 in this drawing Fig. II is shown as a two-jet burner fitted with a wire reigniting coil 10' partially surrounded by shield 11. The reigniter in this case is heated by the heat radiated from both flames and performs the same function as reigniting prongs 10 of the burner shown in Fig. I.

The combustion chamber or lamp top is in this case shown as of the Wolf type and is provided with annular top and bottom reflecting elements 19 and 19^a. The function of reflecting element 19 has been fully described in the description of the drawing Fig. I. That of 19^a is similar, with the difference that the light rays reflected by 19 are directed upward toward the roof while those reflected by 19^a are directed toward the space below the lamp, the approximate path of one such ray being shown by the dot and dash line B—B.

It should be noted, however, that the reflecting element 19^a is not designed to perform the same functions as that of the reflectors commonly used in the so-called "porch" type of safety lamp and that its size should never be so great as to materially cut off the upward rays reflected by element 19. In other words, the function of element 19^a is in all cases subordinate to that of element 19, as inspection of the roof is generally of far greater importance than that of the floor. The light rays indicated by the dot and dash lines A—A and B—B in the several drawings are roughly approximate as no allowance has been made for refraction due to the glass.

The Wolf type of top shown is composed of glass 22, outer gauze 26, inner gauze 27 and bottom air-ring gauze 21, provided with baffle ring 21^b. It is similar to the top in common use with benzine burning safety lamps and hence need not be further described.

Fig. III illustrates an enlarged cross-section of a reigniting burner equipped with exterior shield for preventing loss of heat from the reigniting element. In this case the burner 9, shown as of the single jet type, is provided with helical coil 10" of nickel

alloy wire, this coil 10" forming the reigniting element. The burner together with the reigniting coil is surrounded by a shield 11 provided with air inlet holes 11^a in its lower portion. To secure the best operating result the shield should be made of reflecting material, such as enameled metal, glazed porcelain, plain or mirrored glass, etc., so that it will reflect heat from its interior and 10 radiate a minimum of heat from its exterior. In other words, its function is to return a maximum quantity of the heat received by it from the lamp flame and reigniting element, to said lamp flame and reigniting element, and at the same time to lose by radiation and conduction a minimum quantity of heat. It will of course be understood that 15 the function of the reigniting element is similar to that described in the drawings 20 Figs. I and II.

I have found that by the use of a heat insulating device such as the shield 11 in the drawing Fig. III, a reigniting burner can be successfully operated with a reigniting 25 element that would operate poorly, if at all, when not provided with such a shield. As any light losses of the flame, due to the use of a reigniting element, are largely a function of the mass required by said element and of the proximity of said element to the flame, it will be clear that a device 30 such as the shield 11 which permits the use of reigniters of less mass, and placed farther from the flame, than would otherwise be possible, is exceedingly advantageous in 35 increasing the efficiency of the lamp as a whole. The shield also performs another important function in that it prevents accidental breakage or deformation of the reigniting element when the lamp is being handled during cleaning, etc.

The drawing Fig. IV illustrates a lamp of similar construction to that shown in Fig. I with the exception that the lamp top, 45 or combustion chamber, is of different construction. Said drawing need not be further described, therefore, except in so far as may be required for understanding the operation of this type of combustion chamber.

In this drawing Fig. IV the glass ring support 20 supports a plate 21 carrying tube 21^a, said plate 21 supports outer glass 22, glass chimney 23 and upper plate 24 carrying tube 24^a sliding over tube 21^a. Plate 24 carries chimney 25, outer gauze 26 50 and inner gauze 27 in the same manner that gauze 24 supports these elements in the drawing Fig. I.

60 The function of the plates 21 and 24 and tubes 21^a and 24^a is similar to that performed by gauzes 21 and 24 of the drawing Fig. I. The air for admission passes downward through these plates and tubes 65 and is isolated from the exterior atmos-

sphere, and also from the annular space between the glass 22 and chimney 23. Hence the lamp flame is doubly isolated from the exterior atmosphere, as in the drawing Fig. I, and breakage of the exterior glass alone 70 will not cause passage of flame to the exterior. The incoming air will be pre-heated by passing downward through tubes 21^a and 24^a and these tubes will of course be of such cross-sectional area (or a plurality of 75 such tubes will be used) as to insure sufficient air supply for the proper combustion of the flame. The advantage of this method of construction is that it renders impossible an ascending current of air and a descending current of air in the tubes at the 80 same time, whereas this phenomena might possibly occur in the annular space between the glasses in the double glass type of lamp, such as shown in Fig. I. The result 85 achieved is parallel to that reached in the Gray type of lamp employing exterior tubes for air admission.

To insure the same degree of gauze protection as that shown in Fig. I, it will be 90 understood that one or more gauzes may be placed within these tubes, and also that the tubes should be such a sliding fit over one another as to eliminate the possibility of firing the exterior atmosphere by a leak 95 between the walls of the tubes. The tube 24^a may advantageously support a reflecting element 24^b for projecting the light rays horizontally, as this tube will of course cut off a certain amount of light and this disadvantage may be thus counteracted. It should be noted that this reflecting element 100 would be acting in an absolutely dead atmosphere between the outer and inner chimneys and could therefore be kept clean for 105 comparatively long periods of time.

The use of double glass chimneys with 110 double gauze protection in oil burning safety lamps is known, and has previously been practised in lamps of the Muessler type, but without successful commercial result, as the sooting of the interior glass by the oil-fed flame was found certain to occur whenever the lamps were built with glasses 115 of a size that was practically feasible. It will of course be seen that with a fuel such as acetylene this trouble will not be encountered, and I have found it possible to operate lamps of this type for periods considerably in excess of 100 hours without 120 cleaning the gauzes or glasses, as under all proper operating conditions soot is not deposited by the combustion of the flame.

125 It will of course be understood that the reflecting elements of the type herein described may readily be used with lamps burning liquid fuels, and of the types in common use, and the scope of this invention is not limited to lamps of the gaseous fuel type. It should be pointed out, how- 130

ever, that the low unit illumination of liquid fuel safety lamps does not produce a roof or floor illumination comparable to that possible with the acetylene type of lamp.

It will be understood that any type of combustion chamber, or lamp top, in common use in flame safety lamp structures may be employed in carrying out my invention and that any form of magnetic screw, lead-rivet or other lock may also be employed.

It will be noted in the several drawings that the water chamber is enlarged near its center. This is for the purpose of keeping a more constant head of water during operation than would be the case were a chamber of uniform cross-section employed, and while in no way essential to the operation of my invention, I have found it to be an advantageous type of construction.

The functions of the reigniting burner 9 are fully described in the U. S. Patent 1,198,006 to Thomas M. Chance, and need not be further described here.

It will be understood that the type of generator and shielded reigniting burner herein described may be used with lamps that do not require foraminous or other means for preventing exterior ignitions, such as in ordinary open lights, and that the use of the type of generator and shielded burner in open lamps is entirely within the scope of my invention.

It will be understood that should excessive generation of acetylene occur, the excess gas will blow back through the water in chamber 1 and escape to the exterior atmosphere by means of escape pipe 3. Should the lamp be extinguished by closing the gas valve carried on stem 8, the pressure in the generator, after building up to, or above, the operating head, will be relieved in the above manner, hence as soon as "after-generation" ceases further generation of fresh gas will stop until the gas valve is again opened, permitting the pressure in said generator to fall and fresh water to enter.

The type of mechanical resistance to be used in a water-sealed generator of the kind described herein may be greatly varied, the use of a gasket or screw thread being typical examples of a large class of structures that may be used for reaching the same end. It should be pointed out, however, that whether a separate member, such as a gasket or screw thread, be used, or whether the cover and carbide container be forced together by a close fit, as for example, in a manner simi-

lar to the lid of a tin canister, the mechanical resistance so produced must be sufficient to prevent the flooding of the generator when the lamp is overturned, and also to prevent the water feed working with a higher capillary resistance than the mechanical resistance employed in the water seal. I have found that under certain conditions a continuous over-generation of gas appears to be produced if the water feed be assisted by a high capillary resistance and the water seal is not provided with sufficient mechanical resistance. It will be understood that by the term "mechanical resistance" where used in the specification and claims hereof, is meant any organism acting in conjunction with a water-seal which will so restrict or prevent the free flow of water from the water chamber to the interior of the generator as to attain the ends just described.

The term "foraminous" in the claims and specification hereof is intended to include materials with perforations, apertures or channels through which air may freely pass, but which are too small to permit the propagation of combustion, and I have used the word "foraminous" to designate materials containing such holes, apertures or channels. The term "glass" in the claims and specification hereof is intended to mean any transparent refractory material.

It will also be understood that my invention is not confined to the operation of portable lamp structures, but may be equally well employed with stationary lamps.

Having described my invention I claim:

1. An improved safety lamp comprising in combination a source of combustible gaseous fuel, a reigniting burner adapted to utilize said fuel, a reflecting shield for the insulation of the reigniting element of said burner, and means for preventing the propagation of said flame to the exterior atmosphere.

2. An improved flame lamp comprising in combination an acetylene generator, a reigniting burner adapted to utilize the gas generated therefrom, and a reflecting shield insulating the reigniting element of said burner from external heat losses.

In testimony whereof I have hereunto signed my name at Philadelphia, Pennsylvania, this 25 day of April 1917.

THOMAS M. CHANCE.
